UNITED STATES PATENT OFFICE.

LELAND DALE COLE, OF SHARON, PENNSYLVANIA, ASSIGNOR TO NATIONAL MALLEABLE AND STEEL CASTINGS COMPANY, OF CLEVELAND, OHIO, A CORPORATION OF OHIO.

FURNACE-CHARGING APPARATUS.

Application filed April 8, 1924. Serial No. 704,964.

Fig. 1 is a plan of a melting furnace embodying my invention; Fig. 2 is a side elevation thereof, partly in section; Fig. 3 is a front elevation thereof; and Fig. 4 is a detail showing the means for closing the furnace charging aperture.

My invention relates to charging apparatus for electric or other melting furnaces in which the metal is charged cold. The usual practice in charging a furnace with cold metal is to shovel the charge into the furnace through side doors in the furnace. This practice is extremely laborious and time consuming, and permits the furnace to cool down between heats to such an extent that not only is a large amount of heat wasted, but it is also injurious to the furnace lining. My improved apparatus is designed to lessen the time required for charging by the usual method, reduce the amount of labor required, and minimize both the loss of heat from cooling and the injury to the furnace lining. To this end I have provided a charging port, preferably arranged in the roof of the furnace, into which the cold metal may be admitted from a charging box or other conveying or charging means. I also provide a removable closure for the charging port so that it may be closed thereby and sealed after the furnace has been charged. My invention also comprises the various features which I shall hereinafter describe and claim.

Referring to the drawings, 2 indicates a furnace, which I have shown as an electric furnace of the tilting type having the usual charging doors 3 and electrodes 4, of which I have shown three. Extending through the roof 5 of the furnace and preferably forward of the electrodes is the charging port 6. When the charging operation is in progress a chute, funnel, or guiding means 7 is lowered into the port 6 and is supported therein from the frame-work 8 of the furnace by the extension 9 and the hooked arms 10, in such manner that the roof 5 of the furnace will be relieved of the weight of the chute 7. The bottom 11 of the chute 7 is inclined toward the center of the furnace so that the metal as it is charged will be guided toward the center of the furnace. The upper edge of the chute is in the form of an outwardly and upwardly flaring lip 12, which serves to catch and guide the material as it falls thereinto. The conveying

means as shown comprises a charging box 13 having a forward open end 14.

The frame-work 8 also has mounted upon it a closure or plug 15 for the port 6, which is preferably comprised of a steel ring 16, within which is built up a fire-brick body 17. The closure 15 is suspended from a lever 18 pivoted to the bracket 19 on the frame-work 8. The outer end of the lever 18 is so formed that a pipe handle 20 may be slipped thereon to give increased leverage in moving the closure 15 into and out of the port 6. A chain 21 attached at its ends to the frame-work 8 and to the lever 18 outside of its pivot is also provided, which is so arranged that it will take up and support the weight of the closure 15 both when the closure is in position in the port 6, as is shown in Fig. 4, and also in non-operative position shown in Figs. 1 and 3, for the purpose of relieving the roof 5 of the weight of the closure.

When the furnace is to be charged the electrodes 4 may be elevated to prevent injury to their depending ends by the falling metal, and the closure 15 is swung by the lever 18 out of the port 6 and to one side, as is indicated in Figs. 1 and 3. The chute 7 is then placed in position with its extension 9 seating on an angle piece 22 on the frame 8, and its arms 10 are hooked in the notches 22' of the frame 8. The charging boxes 13, with the metal therein, which is usually in the form of scrap, are lifted by a crane (not shown) one at a time and lowered down until the forward end of the box rests on a cross-piece 23 of the frame between uprights 24, which maintains the forward end of the box in alignment with the chute 7. The crane lifting chain (not shown) is released from the shackles 25 at the forward end of the box and the rear lifting chain 26 is hoisted by the crane so as to tip the box 13 sufficiently to slide the charge of metal down into the chute 7. The inclined bottom 11 of the chute guides the falling metal toward the center of the furnace. If a sufficient distribution of the metal has not been obtained by the charging operation just described the metal may be distributed by slice bars or its distribution equalized by shovelling an additional amount through the usual charging doors 3 in the sides of the furnace.

After the furnace is charged, the chute 7

is removed and the closure 15 is swung over and lowered into the port 6 by the lever 18. The closure is then sealed with fire clay, the electrodes 4 are lowered, and the furnace is ready for the melting operation.

My improved charging apparatus is extremely effective in operation. I have found that by its use not only is the time required for charging very greatly reduced, but the life of the furnace roof is appreciably prolonged, and it enables substantial economies to be effected in the cost of labor and of melting. A further advantage lies in the fact that the operatives are much less exposed to the intense heat of the furnace than with the old practice, and hence there is less difficulty in securing labor for charging furnaces equipped with my invention. My invention also permits the use of a cheaper grade of scrap, such as lathe turnings and the like, since such fine scrap because of its bulk can not be handled readily by the ordinary shovelling method, and therefore heavier grades of scrap are normally utilized.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In furnace charging apparatus, a roof for the furnace having a charging port therein, a removable chute seating in said port, and a removable closure supported on the frame of the furnace arranged to be lowered into the port after the charging operation.

2. In furnace charging apparatus, a furnace having a roof, sides and supporting frame-work; a charging port in the furnace roof; a removable chute seating in said port; a support, forming a portion of said frame-work, for the chute and for a con-

tainer for the metal to be charged, the support comprising means for holding the container in alignment with the chute; and means for closing the port after the charging operation.

3. A metal melting furnace having roof, sides and supporting frame-work, a charging port in the roof, a removable chute seating in the port, a closure arranged to be lowered into the port after the charging operation, the chute and closure when seated in the port being supported from the frame-work to relieve the furnace roof from strain.

4. A metal melting furnace having roof, sides and supporting frame-work, a charging port in the roof, a removable chute seating in the port and having an inclined bottom to direct the charge toward the center of the furnace, and means for closing the port after the charging operation.

5. A metal melting furnace having roof, sides and supporting frame-work, a charging port in the roof, a removable chute having a supporting engagement with the frame-work whereby the chute is suspended in the port during charging, and means for closing the port after the charging operation.

6. A metal melting furnace having roof, sides and supporting frame-work, a charging port in the roof, a removable chute for the metal to be charged arranged to be supported in the port, and a closure depending from a lever pivoted to the frame-work, the closure being arranged upon actuation by the lever to be swung into said port to close it and also into an inoperative position during the charging operation.

7. A metal melting furnace having roof, sides and supporting frame-work; a charging port in the roof; a chute for guiding the charge through the port; a closure arranged to be lowered into the port after the charging operation; the closure when seated in the port being supported from the frame-work to relieve the furnace roof from strain.

LELAND DALE COLE.
